UNITED STATES PATENT OFFICE.

ROBERT CHADWICK AND NORMAN ALLEN, OF HARTFORD, CONNECTICUT,
ASSIGNORS TO ROBERT CHADWICK.

IMPROVEMENT IN MACHINES FOR CASTING BULLETS.

Specification forming part of Letters Patent No. 35,275, dated May 13, 1862.

To all whom it may concern:

Be it known that we, ROBERT CHADWICK and NORMAN ALLEN, both of the city of Hartford, in the county of Hartford and State of Connecticut, have invented a new and Improved Machine for Casting Bullets; and we do hereby declare that the following is a full, clear, and exact description of the same, reference being had to the accompanying drawings, forming part of this specification, in which—

Figure 1 is a top view of the machine. Fig. 2 is a central vertical section of the same. Fig. 3 is a horizontal section of the same.

Similar letters of reference indicate corresponding parts in the several figures.

This invention consists in a machine composed of a series of bullet-molds, such as are used in casting bullets by hand, pivoted to a circular frame, which is arranged to rotate about a central shaft, and which has attached to it a series of levers with appendages which are caused to open and close the molds by the rotation of the levers with the molds around a suitable system of stationary cams. The molds when in a closed condition have the molten lead poured into them one after the other by one or more attendants, and after the metal is set within them are opened to discharge the bullets by the rotation of the circular frame.

To enable those skilled in the art to make and use our invention, we will proceed to describe its construction and operation.

A is a base furnished with a fixed socket, B, in which a shaft, C, is firmly secured in a position slightly inclined from a vertical line.

D is a collar firmly secured to the shaft C for the support of the circular rotating frame E F, which is bored centrally to fit and rotate upon the upper part of the shaft. This frame is made of two separate pieces—viz., a wheel-like piece, E, and a ring, F, secured on the top of the rim of E by screw-bolts b b with intervening studs, a a, to keep the ring at a suitable distance from E for the reception of the molds G G between them. The said molds are or may be constructed like ordinary hand bullet-molds, and are secured in the rotating frame by the elongation of their joint-pins c c to pass through the upper and lower parts of the frame. The molds are arranged with their

handles g g projecting outward beyond the periphery of the rotating frame, and when they are closed their mouths are presented opposite to recesses d d in the upper part, F, of the said frame. Three pairs of nippers only are shown, but there may be a larger number if the rotating frame is made of large enough circumference. The rotating frame and nippers are slightly inclined from the horizontal position, being perpendicular to the inclined shaft C.

H H are the levers for opening and closing the molds, one for each mold, pivoted by fulcrum-pins f to rigid hangers I secured to the bottom of the rotating frame. The upper portions of these levers which are farthest from the shaft are flattened and tapered, as shown at h, to operate as wedges between the handles of the molds to open them, and they have attached to them inverted fork-like pieces i i to lap over the handles g g and operate thereon as wedges to close the molds, and the upper ends have attached weights j j, which tend to pull them down and make the fork-like pieces i i close the molds. J J' are two cams firmly secured on the lower part of the shaft C, the duty of the cam J being to operate upon the inner and upper surfaces of the lower portions of the levers to make them open the molds, and the duty of J' to operate upon the outer and lower surfaces of the said portions of the levers to start them in their movement to close the molds, the latter movement being for the most part produced and completed by the action of the weights j j.

K is a stationary trough secured to the shaft C for the purpose of catching any metal that may overflow in filling the molds.

L is a funnel attached securely to the fixed collar D of the shaft to receive the bullets as they are dropped from the molds by the opening of the latter and conduct them into a spout or chute, M, down which they roll to a suitable receptacle placed under the machine. This spout may be dispensed with and the funnel be made to deliver them directly into the receptacle.

To operate the machine, an attendant (or more than one if the machine is large and has a large number of molds) stands with a ladle of molten lead in one hand opposite to the

lower side of the inclined shaft and turns the frame E F in the direction of the arrow shown in Fig. 1 as often as required by applying his other hand to the handles of the molds to bring them successively to a position to have the lead poured into them. The cams are so arranged as to cause the closing of the molds before their arrival in this position. As each mold is brought to this position he pours the lead into it and turns the machine to bring the next one to the same position and repeats the pouring. As the lower ends of the levers of the several molds arrive and pass in contact with the outer surface of the cam J the said ends of the levers are moved outward from the shaft, and their upper ends are thus moved between the handles of the molds toward their pivots c c, and their wedge-like portions h h are thereby caused to force apart the handles and open the molds to release the bullets which drop out into and through the funnel L. As the rotation of the frame, molds, and levers is continued the lower portions of the levers come in contact with the inner surface of the cam J' and are thereby started toward the shaft, causing the upper portions of the levers to move outward,

and this movement being thus commenced is continued by the weight j, causing the inclined sides of the forks i i by their action on the outer sides of the handles g g to close the molds ready for being refilled with molten lead on their arrival at the proper position. The cam J' may not be necessary as the weights j j may be heavy enough to affect the whole operation of closing the molds; but the said cam is desirable to insure the starting of the levers to close the molds and thereby prevent the possibility of any failure in that part of the operation.

The molds may be of any form to make either spherical or elongated bullets.

What we claim as our invention, and desire to secure by Letters Patent, is—

The combination of a rotating mold-frame, E F, a series of molds, G G, a system of levers, H H, and a cam or canis, the whole applied and arranged to operate substantially as herein specified.

ROBERT CHADWICK.

NORMAN ALLEN.
